J. THOMSON.
ZIGZAG CARBON-ELECTRIC RESISTER.
APPLICATION FILED MAY 28, 1918.

Patented Apr. 1, 1919

UNITED STATES PATENT OFFICE.

JOHN THOMSON, OF NEW YORK, N. Y.

ZIGZAG CARBON ELECTRIC RESISTER.

1,299,265.

Specification of Letters Patent.

Patented Apr. 1, 1919.

Application filed May 22, 1918. Serial No. 236,967.

To all whom it may concern:

Be it known that I, JOHN THOMSON, a citizen of the United States, and a resident of the borough of Manhattan, city of New York, county and State of New York, have invented certain new and useful Improvements in Zigzag Carbon Electric Resistors, of which the following is a specification, reference being made to the accompanying drawing, forming a part thereof.

This invention relates to electric carbon zigzag resistors when employed for radiating heat, as in furnaces and muffles, and an important object of the invention is to construct a resistor comprising a plurality of members the adjacent members of which are spliced or joined in series and in a manner to produce an effective mechanical and electrical joint or connection whereby the resistor as a whole has a large capacity of thermal emission.

As illustrating certain specific embodiments of the invention reference is made to the accompanying drawing and in which the drawing,

Figure 1 is a plan view of a resistor formed of two zig-zag members which are spliced or coupled to each other.

Fig. 2 is a side or edge view of the resistor shown in Fig. 1.

Fig. 3 is an end view of the same resistor.

Fig. 4 is a vertical, transverse section through any of the zig-zag slotted portions; in other words, this figure is a view taken as on the plane indicated by the line A; and

Fig. 5 denotes a modification in a detail of the splice or coupling between adjacent members.

In my Patent No. 1,193,633 of August 8, 1916, and particularly in Figs. 4, 5, 6 and 7 and the relating description and claims thereof, an improvement is set forth in respect of which a portion of the present invention is an amplification.

In the aforesaid patent, the resistor is shown with beveled sides, forming a trapezoidal cross-section. In the present invention, the sides of the resistor, as shown in the several figures, are formed with two bevels, as at C, D, thereby producing a compound trapezoid. In other words, the construction herein shown is similar to that which would be realized if two resistors of the aforesaid patent were laid one on top of the other with their broad faces

in contact. In this wise, when it is desirable to employ a resistor where its heat shall be drawn from its upper and lower faces, or any opposing faces, the excess of current-density, as in the portions from a to b and 60 from c to d, and the excess of radiating and dispersing surface produced by the bevels, will be relatively uniform and symmetrical from both of the flat faces and from both pairs of bevels, as is denoted by the arrows 65 e, h. In other words, the current-density and temperature will uniformly and progressively decrease from the faces of the resistor inwardly to its horizontal center, as line E. There are cases in practice, for example as in heating a square, ovoidal or circular muffle, where this form of resistor is preferable to that illustrated in the patent previously mentioned.

There are also various instances where 75 zig-zag resistors can be most advantageously used of considerably greater length than the carbon or graphite plates or members as ordinarily manufactured. Such conditions can be met by coupling a plurality of plates, 80 end-to-end; but it has hitherto been found exceedingly difficult, complicated and in many instances impracticable, to produce a joint which shall be electrically or mechanically effective and enduring between wide 85 variations in temperature and the deforming stresses imparted to the resistor by the walls of a furnace. The coupling system shown in the drawing is a solution of these difficulties and by its employment an efficient 90 electrical and mechanical joint or coupling is realized between the adjacent zig-zag resistor plates or members. It will be perceived that the resistor as shown in the drawing is composed of two main members, 95 B, B', in which the zig-zags are formed, and two terminals, J, J', without zig-zags; hence involving three coupling-joints. A most effective joint, as respects electrical conductivity and resistance to physical deformation, is produced in the following manner:

The end or ends of each member is machined to produce two transverse faces, as m, n, preferably at an angle of about 5° from the vertical, cross-wise of the plate or 105 slab, and two horizontal plane surfaces as r, s, slightly above and below the horizontal center E of the resistor, and to leave the vertical surfaces v which serve to interlock and resist strains in tension. When the ends are 110

thus machined, as by planing or milling, they may be assembled and one or the other of them slid back and forth cross-wise, or an accurately formed profile gage may be rubbed across the machined surface. Either of these maneuvers will quickly disclose the "high-points" of contact, which are then removed as by filing or scraping, until a practically uniform physical impingement is obtained, say somewhat analogous in its character to that of a ground surface plate.

The next stage of the operation is to clamp or press the coupling members together very snugly by temporary clamping or pressing means, whereby to bring the joint-surfaces into intimate contact.

While maintaining pressure upon the jointed or coupled members, the final stage of the operation is to cross-drill and tap several holes and insert close-fitting headless screws, as *w*, preferably formed of graphitized carbon. The consequences of the foregoing procedure are that the pressure imparted by the temporary clamps will be maintained by the headless screws quite as effectively as if bolts and nuts were employed. Moreover, the ends of the screws can thus be finished flush with the face of the resister and they also serve as additional contacts for electrical conduction between the plates.

The compressed contact of the coupling surfaces can also be maintained by drilling holes half-and-half in each of the sloped vertical sides and driving pins therein, as *p* Fig. 5, which thus function as keys.

Before being clamped together, the faces of the jointing may be coated with graphite powder, or dust, mixed with water to form a paint; which will be caused to flow by the compression, filling any "low spots" in the contiguous surfaces.

A contingent advantage of being able to realize an effective electrical union between two or more plates or slabs is that although the joint may be nearly perfect as a conductor of electricity it yet presents a formidable barrier to the flow of heat; consequently, the thermal losses from the terminals are substantially diminished over that of a zig-zag resister produced from an integral unit.

The use herein of the geometrical terms "trapezoid" and "trapezoidal" is merely to visualize a general form; as it would seem to be apparent that side angles must be adopted which will best conform to various controlling conditions, such, say, as the relation of thickness to width of the plate, the spacing of the zig-zags, etc. Thus, again referring to my cited patent, Fig. 7 thereof shows that the bevels may even be curved. In other words, the precise cross-sectional form is more or less immaterial; provided, however, that the transverse dimensions,

where traversed by the electric current, are less at the faces than at the center of the mass.

A resister of the compound trapezoidal type is particularly useful where it is desirable to draw heat from its opposite upper and lower faces. In such a resister the current-density is the greatest along the upper and lower flat faces, that is, from the portions as *a* to *b* and *c* to *d*. Moreover, with the compound trapezoidal construction the upward and downward radiating and dispersing surfaces are increased over a true rectangular construction due to the bevels *C* and *D* at the sides of the resister. It is fundamental that the radiation of heat from a surface is in a direction normal thereto and this heat radiation is denoted by the arrows, *e* and *h*. With a resister of the compound trapezoidal type the current-density and temperature will uniformly and progressively decrease from the flat faces of the resister inwardly to its horizontal center as indicated by the line *E*.

There are cases in practice, for example as in the heating of a square, ovoidal or circular muffle, where this compound trapezoidal resister is preferable to the form of resister illustrated in the patent aforesaid.

It will also be noted that the screws *w* as well as the locking pins *p* may be broadly referred to as means for maintaining or securing together the adjacent overlapping ends of adjacent zig-zag resister members.

It will also be noted that other forms of securing means can be employed to maintain the zig-zag resister members in assembled position relative to each other when the overlapping and interlocking adjoining portions of adjacent members have been otherwise properly formed and assembled.

What I claim is:

1. A zig-zag carbon resister having a cross-section in the form of a compound trapezoid, whose side-angles are presented to the surfaces, or in the directions, where the radiated heat is to be utilized.

2. A zig-zag carbon resister having a cross-section in the form of a compound trapezoid whose current-density is greatest along zones at or near to both of the horizontal faces which connect with the trapezoidal bevels.

3. A zig-zag carbon resister formed by a plurality of plates transversely interlocked and secured together.

4. A zig-zag carbon resister formed by a plurality of plates transversely interlocked and maintained together by suitable securing means.

5. A carbon resister comprising a plurality of zig-zag resister members, adjacent ends of which are transversely interlocked and secured together by suitable means.

6. A carbon resister having a plurality of

zig-zag members, adjacent ends of which are overlapping, joining portions that are transversely interlocked and that are maintained together by means engaging the overlapping portions.

7. A zig-zag carbon resister comprising a plurality of zig-zag resister members arranged in series and constructed so that the adjacent ends of adjacent members are transversely interlocked, said resister also having means for maintaining said ends in their interlocked positions.

8. A zig-zag carbon resister formed by a plurality of plates having transverse interlocks near their ends and sloped faces which were temporarily compressed and maintained in intimate physical contact by temporary extraneous means, the ends of said plates being permanently secured together in said intimate physical contact by an engaging member or members whose bearings

were formed prior to the removal of the temporary means, the said engaging member or members being inserted prior to the removal of the temporary means.

9. In the forming of carbon resistors the method which comprises providing transversely interlocking portions upon adjacent ends of zig-zag members which are to be connected in series and fitting said ends to each other, compressing said fitted ends and maintaining them in intimate physical contact and while thus maintained securing the ends by suitable means which become a part of the final resister structure.

This specification signed and witnessed this 23d day of May, A. D. 1918.

JOHN THOMSON.
